UNITED STATES PATENT OFFICE.

GEORGE P. KINGSBURY, OF BROOKLYN, NEW YORK, ASSIGNOR TO MERGENTHALER LINOTYPE COMPANY, A CORPORATION OF NEW YORK.

TYPOGRAPHICAL MACHINE.

1,122,609.

Specification of Letters Patent. Patented Dec. 29, 1914.

Application filed October 29, 1913. Serial No. 797,989.

To all whom it may concern:

Be it known that I, GEORGE P. KINGSBURY, a citizen of the United States, residing at Brooklyn, in the county of Kings and State of New York, have invented certain new and useful Improvements in Typographical Machines, of which the following is a specification, reference being had therein to the accompanying drawing.

10 My invention relates to typographical machines, such as linotype machine of the general organization represented in Letters Patent of the United States, No. 436,532, to O. Mergenthaler, wherein circulating matrices are released from a magazine in the order in which their characters are to appear in print and then assembled in line, the composed line transferred to the face of a mold, the mold filled with molten metal to form a slug or linotype against the matrices which produce the type characters thereon, and the matrices thereafter returned through distributing mechanism to the magazine for which they started. More 15 particularly, it relates to typographical machines of this kind, when equipped with plural-letter matrices which are assembled at a common level, and with means whereby the matrices may be then relatively shifted 20 so as to bring a selected line of characters thereon into operative position.

In the present instance, the assembler is preferably provided with matrix supporting rails, which permit the assemblage of the line always at the same level thereon, and with connections whereby the shifting of the assembler automatically changes the level of the rails therein. These connections are under the control of manually operable 35 adjusting means, so that the delivery of the assembled matrices at one level or another may be effected at will.

The specific construction and arrangement of the parts will be described in the specification, and the invention subsequently pointed out in the claims.

50 In the accompanying drawings, I have shown my invention only by way of example and as applied to the style of machine referred to, but obviously many changes and variations may be made therein, and in its mode of application, which will still be comprised within its spirit; and it may be adapted to other forms of typographical

machines, such as typesetters and the like, 55 which handle type or dies, instead of matrices. Generally speaking, I desire it to be understood that I do not limit myself to any specific form or embodiment, except in so far as such limitations are specified in the 60 claims.

Referring to the drawings: Figure 1 is a front view of a portion of a linotype machine having my invention embodied therein; Fig. 2 is a perspective view of my improved devices, the assembler being indicated in dotted lines; Figs. 3 and 4 are end views of the assembler, etc., showing the matrices at different adjusted levels; Fig. 5 is a sectional detail, on an enlarged scale, on 70 the line 5-5 of Fig. 3; and Fig. 6 is a view indicating the matrices in operative relation to the mold at different levels.

Referring to Fig. 1, the matrices are released from the magazine A by the manipulation of the keyboard B, and delivered to the belt C, from which in turn they pass into the assembler D. After composition, the assembler is elevated by the manual operation of the handle E, and the matrices delivered to the slide F, whereby they are transferred to the casting mechanism, all in the usual manner. The parts so far described are or may be of any preferred construction, such as disclosed for instance in 85 the previously mentioned Letters Patent, and their specific form constitutes no part of my invention. The elevating handle E is mounted upon the rock shaft E¹, carrying the arm E², which is connected by the link 90 J to the assembler D in the manner subsequently to be described.

Referring to Figs. 2, 3, 4 and 5, the assembler D is interiorly provided at opposite sides with the inwardly extending supporting rails G, onto which the plural-letter matrices X are delivered at the same level. However, these supporting rails are arranged so as to be movable in a vertical direction relatively to the assembler, in order 95 that one or another of the lines of characters on the matrices may be delivered to the casting mechanism at the operative level. This construction is preferably in the form of an integral skeleton frame, comprising 100 the side extensions H from the rails G and the previously mentioned link J. The connection between this frame and the assem-

bler D is in the form of a transverse bolt K¹ passing through the former and rotatably mounted in the latter. The bolt K¹ is provided at one end with the knurled head K to permit of its ready manual adjustment, and with the projecting extension or lip L located in the square recess or aperture J¹ in the link J. The recess J¹ is of such size and form as to permit the turning 10 of the lip L therein to two different positions, one (Figs. 2, 3 and 5) whereby the skeleton frame is rigidly connected to the assembler,—and the other (Fig. 4) whereby the frame is permitted a limited vertical 15 adjustment with reference thereto. Due to these respective adjustments, the matrices are automatically moved to different operative levels, and so that the slug will be cast from one or another line of characters 20 thereon. When the lip L is turned to the position indicated in Figs. 2, 3 and 5, and the frame and assembler are thus rigidly connected, the operation of the handle E effects the simultaneous elevation of the 25 assembler and frame, and the matrices are delivered at their lower level. When the lip L is turned to the position indicated in Fig. 4, the first effect of the upward movement of the link J, due to the lost motion 30 of the lip in the recess J¹, is to move the ledges G vertically with reference to the assembler and locate the matrices X at their upper level therein; after which the assembler and frame are elevated together. In 35 other words, the manual adjustment of the lip L by the head K permits or prevents the relative movement of the ledges, and thus determines the level at which the matrices are automatically delivered to the transfer 40 slide F and their subsequent casting position.

Fig. 6 illustrates in full and dotted lines the respective operative positions of the matrices with reference to the mold M.

As previously stated, I have shown my invention only in preferred form and by way of example, and as applied to a linotype machine; but obviously many modifications and alterations therein, and in its mode 45 of adaptation, will suggest themselves to those skilled in the art, without departure from its scope.

Having thus described my invention, its construction and mode of operation, what I 55 claim and desire to secure by Letters Patent of the United States, is as follows:

1. In a typographical machine comprising plural-letter type or matrices, the combination of an assembler wherein the matrices are composed in line at one level to 60 bring one set of characters into operative position and from which the composed line is subsequently transferred, and means for shifting the line prior to its transfer to 65 bring a different set of characters into oper-

ative position, the said means being controlled automatically by the normal operation of the machine.

2. In a typographical machine comprising plural-letter type or matrices, the combination of an assembler wherein the matrices are composed in line, and provided with means for supporting the composed line with one set of characters in operative position, and means for shifting the supporting means in relation to the assembler to bring a different set of characters into operative position, the said shifting means being controlled automatically by the normal operation of the machine. 70

3. In a typographical machine comprising plural-letter type or matrices, the combination of an assembler wherein the matrices are composed in line at one level to bring one set of characters into operative 85 position, and from which the composed line is subsequently transferred, means for automatically shifting the line to a different level prior to its transfer to bring a different set of characters into operative position, 90 and manually operable devices for controlling the action of said automatic means.

4. In a typographical machine comprising plural-letter type or matrices, the combination of an assembler wherein the matrices are composed in line, and provided with means for supporting the composed line with one set of characters in operative position, automatic mechanism for shifting the supporting means in relation to the assembler to bring a different set of characters into operative position, and manually operable devices for controlling the action 95 of said mechanism. 100

5. In a typographical machine comprising plural-letter type or matrices, the combination of an assembler wherein the matrices are composed in line, and provided with a relatively movable support to sustain the composed line at different operative 105 levels therein so as to bring one or another set of characters into operative position, means for moving the assembler, and mechanism whereby the movement of the assembler effects the relative movement of said 110 support. 115

6. In a typographical machine comprising plural-letter type or matrices, the combination of an assembler wherein the matrices are composed in line, and adapted to be raised from and lowered to the composing position, a relatively movable support carried by the assembler for sustaining the composed line at different levels therein so as to bring one or another set of characters 120 into operative position, and automatic means whereby the support is moved as the assembler is raised and lowered, for the purpose 125 described.

7. In a typographical machine comprising 130

ing plural-letter type or matrices, the combination of an assembler wherein the matrices are composed in line, with one set of characters in operative position, and from which the composed line is subsequently transferred, automatic means for shifting the composed line vertically to bring a different set of characters into operative position prior to such transfer, and devices for preventing the action of said means when desired.

8. In a typographical machine comprising plural-letter type or matrices, the combination of an assembler wherein the matrices are composed in line, and provided with a relatively movable support for sustaining the composed line at different levels therein to bring one or another set of characters into operative position, automatic means for moving said support, and devices for preventing the action of said means when desired.

9. In a typographical machine, the combination of a vertically movable assembler, wherein the line is composed, a relatively

movable support carried by the assembler for sustaining the composed line at different operative levels therein, means for moving the assembler, and intermediate adjustable connections between said means and support, whereby the movement of the assembler will or will not effect the relative movement of the support, according to the adjustment of said connections.

10. In a typographical machine comprising plural-letter type or matrices, the combination of a movable assembler wherein the matrices are composed in line and carrying a relatively movable support to sustain the composed line at different levels therein to bring one or another set of characters into operative position, means for moving said support, and further means to lock the support against movement when desired.

In testimony whereof I have affixed my signature in presence of two witnesses.

GEORGE P. KINGSBURY.
